UNITED STATES PATENT OFFICE.

CHARLES W. LAKEY AND EDWARD L. CROUCH, OF WINSTON-SALEM, NORTH CAROLINA, ASSIGNORS TO E. LEWIS EVANS, SECRETARY-TREASURER OF THE TOBACCO WORKERS INTERNATIONAL UNION, OF LOUISVILLE, KENTUCKY.

LABELING MACHINE.

Application filed March 15, 1923. Serial No. 625,365.

To all whom it may concern:

Be it known that we, CHARLES W. LAKEY and EDWARD L. CROUCH, citizens of the United States, residing at Winston-Salem, 5 in the county of Forsyth and State of North Carolina, have invented certain new and useful Improvements in Labeling Machines; and we do hereby declare the following to be a full, clear, and exact description of the 10 invention, such as will enable others skilled in the art to which it appertains to make and use the same.

This invention relates to a machine for affixing labels and the like to cartons.

15 The object of the invention is to provide a machine of an improved and simplified character adapted to automatically and successively align the container, apply an adhesive to the container, sever and apply 20 labels supplied to the device in the form of a continuous strip in roll form.

Further objects will appear more clearly in connection with the following detailed description in connection with the various 25 features of the invention.

The invention consists of the novel construction, arrangement and combination of parts, as hereinafter more particularly described and claimed.

30 Four sheets of drawings accompany this specification as part thereof, in which like reference characters indicate similar parts throughout.

Fig. 1 is a front elevation of the improved 35 machine.

Fig. 2 is a plan view.

Fig. 3 is an end elevation from the left of 40 Fig. 1.

Fig. 4 is a transverse vertical section taken on the line 4—4 of Fig. 2.

Fig. 5 is a transverse vertical section taken on the line 5—5 of Fig. 2.

Fig. 6 is a transverse vertical section taken on the line 6—6 of Fig. 2.

45 Fig. 7 is a detail of the operating mechanism for the adhesive rollers.

Fig. 8 is a detail view of the cutter device.

Fig. 9 is a detail view of the label affixing means.

50 Fig. 10 is a detail view of the label cutting and label affixing devices removed from but shown in relation to the guides for these parts on the framework.

Fig. 11 is a detail front elevation of the

driving mechanism for the adhesive applying devices.

In accordance with the present invention a suitable table top frame 1 is provided having mounted thereon longitudinally extending shafts 2 and 3. Shaft 3 is provided with a pulley 4 in association with a clutch 5 operated as by hand lever 6 by means of which operating power may be applied to the machine as desired. On shaft 2 are pivotally mounted levers 7, 8, 9, 10 and 11, which extend substantially vertically and are each provided with rollers 12 adapted to contact cam members 13, 14, 15, 16 and 17 mounted upon shaft 3 and angularly disposed with reference to each other so as to operate in succession and in proper predetermined order the levers 7, 8, 9, 10 and 11 which levers are normally held with their rollers 12 in engagement with their respective cam members by means of suitable springs 81, having one end secured to a suitable part of the frame 1, such as bar 82.

Mounted upon the top of frame 1 at the right-hand end thereof, is a plate 23 provided with a bore adapted to receive a plunger 24, provided upon its front end with a contact member 25 preferably of rubber or some other suitable material and formed adjacent its rear end with a collar 26 between which and plate 23 is secured the compression spring 27 tending normally to retain the plunger 24 in a retracted position. The rear end of plunger 24 is adapted to be engaged by a shoe 29 mounted upon the upper end of lever 7 so that upon the operation of lever 7 by the rotation of cam 13 plunger 24 will be projected forward over the front of frame 1 to engage a container 22 passing before the plunger upon any suitable conveyor as belt 21, to properly position the container on said belt for the succeeding operations.

Adjacent plate 23 and on top of the frame 1 are secured two vertical standards 30 adapted to support the adhesive applying mechanism as illustrated in Figures 5 and 6. Secured on the front of standards 30 adjacent their top is an open-topped container 31 adapted to receive the adhesive fluid 34. Within the container 31 is mounted a roller 32 as upon shaft 36' and a suitable wiper knife 35 is provided, adapted to remove surplus adhesive from this roller.

Above roller 32 and in contact therewith, a second distributing roller 33 is mounted upon shaft 36 and the two rollers 32 and 33 are rotated in unison but in opposite directions by means of mesh gears 37 and 37' located exteriorly of container 31. Power is applied to rotate the rollers through shaft 36 of roller 33 upon which is mounted a ratchet wheel 38 adapted to be operated by pawl 39, pivoted to one arm 40 of a bell crank 45, the other arm 44 of which is adapted to be engaged by a head 43 projecting laterally from a lever 42 secured to shaft 41, upon which the bell arm 45 is pivotally mounted. On shaft 41 is also secured an arm 46 carrying on its outer end a spindle 47 to which spindle is secured a wiper arm 48 provided with a paster foot 49. A pulley 50 is secured to spindle 47 over which passes a belt 51, which is crossed and then passed over a pulley 52 secured coaxially with shaft 41 but secured against rotation by attachment, as through screws 80, to one of the vertical standards 30. A driving gear 53 is secured to shaft 41 and is meshed with a quadrant gear 54 mounted upon standard 30 and secured as by connecting arm 55 with lever 8.

The operation of this mechanism is as follows:

The rotation of cam 14 will operate lever 8 and thus rotate quadrant 54 which will in turn rotate shaft 41, swinging arm 46 from its upper position as illustrated in Figure 5, to its lower position as illustrated in Figure 11, (see Fig. 6), at the same time pulley 50 and hence spindle 47 will be rotated, swinging paster foot 49 from one side of lever 46 to the opposite side so that in both the elevated and lowered positions of lever 46 the paster foot 49 will be outwardly directed.

At the same time lever 42 secured to shaft 41 will engage arm 44 of bell crank 45, thus operating pawl 39, ratchet wheel 38 and rollers 32 and 33 to expose a fresh supply of adhesive to the returning paster foot. The parts are so arranged and dimensioned that in its lowermost position the paster foot will contact a container 22 previously aligned by plunger 24 and apply to a part thereof, a coating of adhesive.

Mounted on the top of frame 1 adjacent the adhesive applying mechanism just described are two vertically disposed standards 56, having adjacent their tops slots 57 adapted to receive a spindle 58 upon which is mounted a roll of labels in strip form, said strip being designated by reference 60. This strip is fed downwardly between standards 56 over a guide pulley 61 and between tension pulleys 62-62'. Tension pulley 62 is mounted upon a shaft 67, slidably secured in guides 69 and subject to the tension of a spring or other compression member 70

tending to normally force said roller 62 against roller 62'. From between these rollers the strip projects downwardly between two spaced guide members 66 having its edges guided therein as by grooves 65. Above and immediately adjacent the guide members 66 is secured a knife 64 secured as by part 75 to the standard 56, the knife 64 cooperating with a sliding beveled knife part 63 operated by rod 76, which is pivotally connected to lever 9. Beneath the knife edges and between guide members 66 is a plunger 77 secured to rod 78 pivotally secured to lever 10. The tension roller 62 is positively rotated by means of a ratchet wheel 71 secured on shaft 67, which ratchet wheel is engaged by pawl 72 pivoted to a double armed lever 73, the other arm of which is connected by rod 74 with lever 11.

In operation cam 15 will operate lever 9, thus operating knife 63 through rod 76 to sever the portion of the label strip between the guide members 66. At this point cam 16 will operate lever 10 to operate plunger 77, which will push forward the severed label and apply the same to the container 22, previously aligned by plunger 24 and coated with adhesive by paster foot 49 as above described.

Cam 17 in turn operates lever 11 to rotate tension roller 62 and thus feed down the label strip between the guides 66 for a repeat operation.

Various modifications in the precise form and arrangement of parts will readily suggest themselves to those skilled in the art but within the scope of the present invention as claimed.

What we claim is:

1. In an adhesive applying device a rotary arm, a wiper arm having a paster foot rotatably mounted on the free end of the arm and means for simultaneously rotating said arm and wiper arm each substantially 180°.

2. In a device of the character described in combination with adhesive distributing rollers, a rotary arm, a wiper arm having a paster foot rotatably mounted on the free end of the arm and means for rotating the adhesive rollers and rotating the arm and wiper arms simultaneously through substantially 180°.

3. In an adhesive applying device a shaft, a rotary arm mounted on the shaft carrying on its free end a spindle with a rotary wiper arm mounted thereon, a fixed pulley coaxial with the shaft and a pulley secured to the spindle, said pulleys connected by a crossed belt and means for rotating the shaft in alternately opposite directions.

4. In an adhesive applying device a shaft, a rotary arm mounted on the shaft carrying on its free end a spindle with a rotary wiper arm mounted thereon, a fixed pulley coaxial

with the shaft and a pulley secured to the spindle, said pulleys connected by a crossed belt, adhesive distributing rollers connected by co-meshing gears and having a driving 5 ratchet wheel, a bell crank freely mounted on the shaft having a pawl pivoted to one arm adapted to engage the ratchet wheel, a lever secured to the shaft having an offset head to engage the other arm of the bell crank 10 and means for rotating the shaft in alternately opposite directions.

5. A label feeding severing and applying means comprising standards adapted to support a roll of labels in strip form guide and 15 feed rollers located between the standards to feed the strip downward, spaced guides between the standards to receive the marginal edges of the end of the label strip, shearing means located above said guides, a plunger 20 affixing means reciprocable between said guides and means for operating the feed

rollers, shearing means and affixing plunger in succession in predetermined order.

6. A device of the character described comprising a frame, a shaft extending longitudinally of the frame, a plurality of cams mounted on the shaft in a predetermined angularity relative to each other, a plurality of spring controlled levers vertically mounted on the frame one for each cam and aligning mechanism, adhesive applying mechanism and label feeding severing and affixing mechanism mounted on the frame and in association with said levers respectively whereby the rotation of the shaft will operate said levers successively in predetermined order to operate said mechanisms, substantially as specified. 25 30 35

In testimony whereof we affix our signatures.

CHARLES W. LAKEY.
EDWARD L. CROUCH.
